CORPORATION OF GERMANY

SCREENING PLANT

Application filed September 6, 1928, Serial No. 304,280, and in Germany May 7, 1928.

This invention relates to a screening plant with mass-balanced screens suspended in a frame by means of guide rods, and working in opposite directions. It differs from known arrangements of this kind in that the screens are not coupled together in a positive manner, but are merely connected together indirectly by means of the frame, and in that their movement is regulated, by means of a triple kind of elastic damping devices, in such a way that the entire system is set in motion by a single connecting rod, and changes in the number of revolutions of the motive machine produce changes in the stroke of the screening movement without affecting the period of oscillation of the screens.

The arrangement of the elastic damping devices extends to the frame which carries the screens and is longitudinally displaceable on its sub-structure under the influence of said devices; to the suspension of the screens on the frame, by which means their period of oscillation is regulated; and to the connection of the point of application of the connecting rod which acts on one of the screens.

These three elastic dampings acting on the system at three different points of the three different reciprocating movements (thrust-rod movement, screen movement and frame movement) co-act in such a manner that on starting, the movement of the connecting rod is smoothly and gradually transformed into the movement of the screen with which it is directly connected, and then the movement of this screen is transmitted, through the agency of the now oscillating frame, to the second screen, which is set in periodic oppositely directed oscillation, until a certain period of oscillation, specific for the entire system, is attained, the maintenance of which requires a minimum of motive power.

The elastic damping of the connecting rod, is so calculated that said damping ceases to operate when the normal working oscillation is attained; that is to say the spring interposed between the screen and the connecting rod then acts like a rigid member.

In view of the action to be obtained, the values of the elastic damping of the screen

movement and the frame movement also bear a certain relation to the damping of the connecting rod and to each other. The elasticity of all three dampings is such that the energy stored up, every time, during the one direction of oscillation, is completely utilized during the return oscillation.

Both screens are suspended on obliquely disposed guide rods, all parallel to one another and thereby producing the known hopping progressive movement of the material on the screens.

For the purpose of maintaining a certain maximum oscillation of the screens, means may be provided for automatically regulating the speed of the motive machine.

A typical embodiment of the invention is illustrated on the accompanying drawing, in which Fig. 1 is a side elevation (that portion of the frame situated in the plane of the drawing and to the right of the line of fracture X—X, being removed) and Fig. 2 is a plan.

In the embodiment illustrated, two independent screens *b* and *b'* are mounted in series, at different levels, in a frame *a* of box or similar type, being movably suspended by obliquely disposed parallel guide rods *c*. The frame *a* is supported, with the interpolation of rollers *e*, on a sub-structure *d*, and the movement of the frame on said rollers is restricted and damped by springs *f* arranged between the frame and the sub-structure. Said springs *f* are preferably located midway of the length of the frame, but they may also be disposed in any other suitable place.

The upper screen *b* is driven by a motor *g* secured on the frame *a* and acting through an eccentric *h* and a connecting rod *i*, which is connected with said screen *b* in a non-rigid manner, being elastically attached thereto by means of a spring *k* so that, when the connecting rod is set in motion, said spring is first stretched, but co-acts in the system, like a rigid member, when the working speed is attained.

The oppositely-directed motion of the second screen *b'* is produced by means of spring devices *l*: *l'*, the former of which transmits

the movement of the connecting rod i , or screen b , to the frame a , whilst the second spring device transmits the movement of the frame a to the screen b' .

5 The difference between the long lever action of the links c and the short lever action of the rollers e on the one hand and the fact that on the other hand the frame a is of considerable weight and therefore of considerable inertia co-operate to produce the result that the movement of the frame by means of the spring coupling l is transmitted to the screen b' in such a manner that this freely swinging screen, a short time after the 10 motor g is set in motion executes a movement opposite to the movement of the screen b . This counter movement is brought about by the use as an intermediate slide between the two screens of the frame whose mass far 15 exceeds the mass of the two screens and in this manner the frame has a movement independent of all others.

Any change which may occur in the phase does not effect an efficient working of the 20 screen.

While the motor is running at normal working speed and the connecting rod i is describing a corresponding number of strokes, the oscillations of all the moving 25 masses in the plant are balanced in such a way that the apparatus is kept running by a minimum amount of force, which is inferior to the elasticity of the spring k , the latter therefore acting as a rigid member.

30 Since, apart from the stroke (which may be adjustable) of the eccentric, the amplitude of movement of the screens is dependent on the speed of the motor, provision is made, according to the invention, for automatically regulating the motor speed. For this purpose, there is inserted in the circuit of the working current a series resistance which 35 operates in the following manner:—If, from any cause, the speed of the motor increases to an undue extent, and the stroke of the screens b ; b' consequently becomes excessive, an electrical resistance o is connected up in the working circuit by means of a stop m disposed on the screen b' and acting through 40 lever mechanism $n: r$, so that the motor slows down at once. During the consequent reduction in the stroke of the screen, the resistance is slowly cut out again, automatically, by reason of the fact that the switch lever n is 45 turned to its normal position by the action of a damping return device p .

In order to prevent clogging of the screen, for example in screening wet coal, provision is made for increasing the working current 50 (independently of the aforesaid automatic regulating device) by switching out a special series resistance, and thereby intentionally increasing the stroke, at certain intervals, beyond that which is generally desirable.

55 Having now fully described our invention

what we claim and desire to secure by Letters Patent is:—

1. A screen plant comprising, in combination, mass-balanced screens, a frame, a stationary sub-structure adapted to support said frame, elastically damped connecting means coupling said frame to said sub-structure, means whereby said screens are suspended in said frame, elastically damped connecting means coupling each screen to said frame independently, reciprocating means, and elastically damped connecting means coupling said reciprocating means to one screen thereby causing the screens to oscillate in opposite directions. 80

2. A screening plant comprising, in combination, mass-balanced screens, a frame, a stationary sub-structure adapted to support said frame, elastically damped connecting means coupling said frame to said sub-structure, means whereby said screens are suspended in said frame, elastically damped connecting means coupling each screen to said frame independently, a connecting rod, rotary driving means on said frame adapted to reciprocate said rod, and elastically damped connecting means coupling said rod to one screen, thereby causing the screens to oscillate in opposite directions. 85

3. A screening plant comprising, in combination, mass-balanced screens, a frame, a stationary sub-structure adapted to support said frame, oppositely acting spring means connecting said frame to said sub-structure, means whereby said screens are suspended in said frame, elastically damped connecting means coupling each screen to said frame independently, reciprocating means, and oppositely acting spring means connecting said reciprocating means to one screen thereby 95 causing the screens to oscillate in opposite directions. 100

4. A screening plant comprising, in combination, mass-balanced screens, a frame, a stationary sub-structure adapted to support said frame, elastically damped connecting means coupling said frame to said sub-structure, means whereby said screens are suspended in said frame, oppositely acting spring means connecting each screen to said frame independently, reciprocating means, and elastically damped connecting means coupling said reciprocating means to one screen, thereby causing the screens to oscillate in opposite directions. 110

5. A screening plant comprising, in combination, mass-balanced screens, a frame, a stationary sub-structure adapted to support said frame, oppositely acting spring means connecting said frame to said sub-structure, means whereby said screens are suspended in said frame, oppositely acting spring means connecting each screen to said frame independently, a connecting rod, rotary driving means on said frame adapted to reciprocate 115 120 125 130

- said rod, and oppositely acting spring means connecting said rod to one screen thereby causing the screens to oscillate in opposite directions.
6. A screening plant comprising, in combination, mass-balanced screens, a frame, a stationary sub-structure adapted to support said frame, elastically damped connecting means coupling said frame to said sub-structure, means whereby said screens are suspended in said frame, elastically damped connecting means coupling each screen to said frame independently, reciprocating means, means for regulating automatically the speed of operation of said reciprocating means, and oppositely acting spring means connecting said reciprocating means to one screen thereby causing the screens to oscillate in opposite directions. 70
- 10 7. A screening plant comprising, in combination, mass-balanced screens, a frame, a stationary sub-structure adapted to support said frame, elastically damped connecting means coupling said frame to said sub-structure, means whereby said screens are suspended in said frame, elastically damped connecting means coupling each screen to said frame independently, reciprocating means, and elastically damped connecting means coupling said reciprocating means to one screen, thereby causing the screens to oscillate in opposite directions. 80
- 15 8. A screening plant comprising, in combination, mass-balanced screens, a frame, a stationary sub-structure adapted to support said frame, elastically damped connecting means coupling said frame to said sub-structure, means whereby said screens are suspended in said frame, elastically damped connecting means coupling each screen to said frame independently, a rigid connecting element, rotary driving means on said frame adapted to reciprocate said element, elastically damped connecting means coupling said element to one screen thereby causing the screens to oscillate in opposite directions, a stop member on one of the screens, a switch on said frame operable by said member when said driving means exceeds normal speed, and a control device in operative connection with said switch so as automatically to regulate the speed of said driving means. 85
- 20 9. A screening plant comprising, in combination, mass-balanced screens, a frame, a stationary sub-structure adapted to support said frame, elastically damped connecting means coupling said frame to said sub-structure, means whereby said screens are suspended in said frame, elastically damped connecting means coupling each screen to said frame independently, reciprocating means, and elastically damped connecting means coupling said reciprocating means to one screen, said reciprocating means having elasticity and being dimensioned to act as a rigid member at normal screening speed. 90
- 25 10. A screening plant comprising, in combination, mass-balanced screens, a frame, a stationary sub-structure adapted to support said frame, elastically damped connecting means coupling said frame to said sub-structure, guide members whereby said screens are suspended in said frame, elastically damped connecting means coupling each screen to said frame independently, reciprocating means, and elastically damped connecting means coupling said reciprocating means to one screen, thereby causing the screens to oscillate in opposite directions. 95
- 30 11. A screening plant comprising, in combination, mass-balanced screens, a frame, a stationary sub-structure adapted to support said frame, elastically damped connecting means coupling said frame to said sub-structure, springy guide rods whereby said screens are suspended from said frame, elastically damped connecting means coupling each screen to said frame independently, reciprocating means, and elastically damped connecting means coupling said reciprocating means to one screen, thereby causing the screens to oscillate in opposite directions. 100
- 35 12. A screening plant comprising, in combination, mass-balanced screens, a frame, a stationary sub-structure adapted to support said frame, oppositely acting spring means connecting said frame to said sub-structure, springy guide rods whereby said screens are suspended from said frame, oppositely acting spring means connecting each screen to said frame independently, a connecting rod, rotary driving means on said frame adapted to reciprocate said rod, and oppositely acting spring means connecting said rod to one screen, said reciprocating means having elasticity and being dimensioned to act as a rigid member at normal screening speed. 105
- 40 13. A screening plant comprising, in combination, mass-balanced screens, a frame, a stationary sub-structure adapted to support said frame, oppositely acting spring means connecting said frame to said sub-structure, springy guide rods whereby said screens are suspended from said frame, oppositely acting spring means connecting each screen to said frame independently, a connecting rod, rotary driving means on said frame adapted to reciprocate said rod, oppositely acting spring means connecting said rod to one screen and so made in relation to the spring means between the frame and screens and 110
- 45 14. A screening plant comprising, in combination, mass-balanced screens, a frame, a stationary sub-structure adapted to support said frame, oppositely acting spring means connecting said frame to said sub-structure, springy guide rods whereby said screens are suspended from said frame, oppositely acting spring means connecting each screen to said frame independently, a connecting rod, rotary driving means on said frame adapted to reciprocate said rod, oppositely acting spring means connecting said rod to one screen, said reciprocating means having elasticity and being dimensioned to act as a rigid member at normal screening speed. 115
- 50 15. A screening plant comprising, in combination, mass-balanced screens, a frame, a stationary sub-structure adapted to support said frame, oppositely acting spring means connecting said frame to said sub-structure, springy guide rods whereby said screens are suspended from said frame, oppositely acting spring means connecting each screen to said frame independently, a connecting rod, rotary driving means on said frame adapted to reciprocate said rod, oppositely acting spring means connecting said rod to one screen, said reciprocating means having elasticity and being dimensioned to act as a rigid member at normal screening speed. 120
- 55 16. A screening plant comprising, in combination, mass-balanced screens, a frame, a stationary sub-structure adapted to support said frame, oppositely acting spring means connecting said frame to said sub-structure, springy guide rods whereby said screens are suspended from said frame, oppositely acting spring means connecting each screen to said frame independently, a connecting rod, rotary driving means on said frame adapted to reciprocate said rod, oppositely acting spring means connecting said rod to one screen, said reciprocating means having elasticity and being dimensioned to act as a rigid member at normal screening speed. 125
- 60 17. A screening plant comprising, in combination, mass-balanced screens, a frame, a stationary sub-structure adapted to support said frame, oppositely acting spring means connecting said frame to said sub-structure, springy guide rods whereby said screens are suspended from said frame, oppositely acting spring means connecting each screen to said frame independently, a connecting rod, rotary driving means on said frame adapted to reciprocate said rod, oppositely acting spring means connecting said rod to one screen, said reciprocating means having elasticity and being dimensioned to act as a rigid member at normal screening speed. 130

between the frame and sub-structure that at normal speed the said connecting means between said screen and rod acts as a rigid member, a stop member on one of said screens, a switch on said frame operable by said member when said driving means exceeds normal speed, and a control device in operative connection with said switch so as automatically to regulate the speed of said driving means.

14. A screening plant comprising, in combination, a pair of mass-balanced screens, a frame, a fixed sub-structure adapted to support said frame, elastically damped connecting means coupling said frame to said sub-structure, springy guide rods whereby said screens are suspended in said frame, inclined members secured to said frame and slidably engaged by one of said screens, separate inclined members secured to said frame and slidably engaged by the other screen, springs interposed between said frame and screens on each inclined member, reciprocating means, and elastically damped connecting means coupling said reciprocating means to one screen so as to ensure oscillation of the screen in opposite directions.

15. A screening plant comprising in combination a pair of mass-balanced screens, a frame of open box-shape, a fixed sub-structure adapted to support said frame, oppositely acting spring means connecting said frame to said sub-structure, parallel inclined guide rods whereby said screens are suspended from said frame, inclined members secured to said frame and slidably engaged by one of said screens, separate inclined members secured to said frame and slidably engaged by the other screen, springs interposed between said frame and screens on each inclined member, a rigid connecting element, an electric motor on said frame, driving connection between said motor and said element, and oppositely acting spring means connecting said element to one screen so as to effect oscillation of the screens in opposite directions.

In testimony whereof we affix our signatures.

50 HANS BINTE.
WERNER PIPKORN.
